CLAIM

The ornamental design for the bushing for swimming pool cover axel, shown and described.

DESCRIPTION

FIG. 1 is a top, front and left side perspective view of a bushing for swimming pool cover axel showing my new design.

FIG. 2 is a top plan view thereof.

FIG. 3 is a side elevational view thereof, the opposite side being substantially identical.

FIG. 4 is a front elevational view thereof, the rear view being a mirror image. The undisclosed bottom is flat and unornamented.
